[57] CLAIM

The ornamental design for a free standing light fixture, as shown and described.

DESCRIPTION

FIG. 1 is a perspective view as seen from the top, front and one side of the free standing light fixture showing my new design;

FIG. 2 is a top plan view of the fixture;

FIG. 3 is a front elevational view of the fixture; and,

FIG. 4 is a bottom plan view of the fixture.

The cross-hatching is partially shown on the top and bottom surfaces of the light emitting portion of the fixture for convenience of illustration, it being understood that the cross-hatching is continuous over the surfaces indicated.
